BOTTOM MARGIN INDICATING MECHANISM FOR TYPEWRITERS

Philip J. Linskey, Coral Gables, Fla.

Application September 22, 1949, Serial No. 117,179

2 Claims. (Cl. 197—141)

1

The present invention relates to typewriters, but more particularly to margin spacing devices. Most typewriters have some form of structure for preventing the typed lines from running too close to the side edge of the paper. This structure usually includes a yieldable bell ringing lever and a positive stop which are successively operated by a finger attached to the platen carriage. In case it is desired to type closer to the side margin than would normally be permitted by the margin stop, a special margin stop lever is provided adjacent the key-board which, when depressed, releases the margin stop and permits the platen to move past the predetermined stopping point.

In case a margin of desired width must be maintained at the bottom of the sheet, it is customary for the typist to watch for the numbered lines on the sheet and estimate when the last permissible typed line has been reached. This estimate is sometimes facilitated by the use of a drum on the platen which shows the number of revolutions made by the platen, and therefore the number of lines typed, in order to ascertain the proper margin.

The primary object of the invention is to provide an improved bottom margin stop for typewriters which is easy to install and positive in operation.

Another object is to provide a bottom margin stop which requires minimum mechanism, and preferably utilizes some of the elements which have already been provided to give a side margin stop.

A further object is to provide a bottom margin stop which can be rendered inoperative at will by the typist, either before or after giving a bell ringing warning that the margin line is about to be reached.

Another object is to provide a bottom margin stop in which a bell ring is automatically caused when the last permissible line is about to be reached, and then continued movement of the platen will cause a positive lock to come into operation which, however, can be released by the typist in order to permit finishing up the last line.

Another object is to provide a bottom margin stop which can be released at any time, but furnishes an indication to the typist every time a line is typed below the predetermined margin.

The final object is to provide a combined bottom margin indicating and stop mechanism of a relatively inexpensive type, which employs as much as possible, some of the standard accessories found on the ordinary typewriter and in

2

which the usual function of these accessories is in no way disturbed or altered, and yet such accessories operate in combination with additional devices to provide a bottom margin stop as well as serving as a side margin indicator and stop.

The above objects are carried out in brief by providing a pair of spring urged levers or fingers attached to the platen carriage and positioned 10 in juxtaposed relation, but adapted to be spread apart by the thickness of the sheet or sheets being typed. One finger or lever is caused to be operated by the other finger when the paper sheet passes entirely past the position where the fingers 15 come into contact with one another, and the finger which is so actuated, has a bell crank extension which is moved into the path of the usual margin indicating and stop devices. Thus, the first-mentioned finger is held in check by the 20 paper so that when the lower edge of the paper passes the position of the point of contact between the fingers, indicating that the margin for the last line of typing has been reached, the second finger is caused to move outwardly to 25 contact the indicating and stop devices. The latter can be removed from the path of the finger by the usual margin release, so that additional lines can be typed beyond the predetermined margin, the same as in the case of the side margin release.

30 Other objects and features will be apparent as the specification is perused in connection with the accompanying drawings, in which:

Figure 1 represents a fragmentary perspective view of a typical typewriter provided with the 35 improved bottom margin indicating and stop mechanism.

Figure 2 is also a perspective view in fragmentary form of the improved typewriter, taken from the front right-hand corner thereof, and with the platen removed from the carriage in 40 order more clearly to show the bottom margin indicating and stop devices.

Figure 3 is a perspective view of the ordinary 45 arcuate form of paper guide, the latter being provided with one of the extensions or fingers which initiates the indicating and stop mechanism.

Figure 4 is a sectional view, partly in elevation, of the platen and the bottom margin indicating and stop mechanism, showing the manner 50 in which the actuating lever or finger moves from a position which is out of the path of the indicating and stop mechanism, into the path thereof, when the predetermined bottom margin has been reached.

Figure 5 represents an enlarged perspective

view of a detail of the mechanism, specifically showing the spring by which a constant urge is applied to each of the two actuating levers forming part of the margin stop mechanism.

Referring more particularly to Figures 1 and 2, reference character 1 designates a wooden base on which the typewriter is mounted at the circular pads 2. The typewriter frame indicated at 3 has a generally rectangular configuration, and is provided with the usual top member 4 and typing elements 5, together with the usual keyboard (not shown). The platen 6 is carried on the usual type of carriage indicated generally at 7, this carriage and its platen being adapted to move transversely of the machine when the keys are struck or the spacer (not shown) is operated. The platen carriage is provided with the usual paper release lever 8 which controls the pressure of the rolls 9 mounted on a swingable frame 10. There is also the usual hand-operated line spacing lever 11, and a pair of levers mounted at opposite ends of the carriage for releasing the mechanism, which correlates the longitudinal movement of the carriage with the keys, so that the carriage and platen can be moved quickly back to its initial starting position. One of these levers is illustrated in Figure 1 and indicated at 12.

In addition to the above elements, the platen carriage is provided with the usual slide bar 13 which carries a pair of margin slide blocks 14, one of which, the left-hand one as shown in Figure 1, has a downwardly extending rod 15. This rod is permanently positioned in the path of a side margin bell lever 16 which it strikes as the platen moves from left to right (as seen in Figure 1), to sound a bell. The lever 16 is adapted to swing in a horizontal direction, and upon continued movement of the rod 15 as the typing proceeds along the same line, the lever withdraws itself from the path of the rod and the latter then travels a little farther to strike the yieldable stop lever 17. This last-mentioned lever is provided with a hook which, upon moving in a horizontal direction, serves eventually to hold the rod 15 fast and thus stop further movement of the platen carriage.

The levers 16 and 17 are carried on a horizontal arm which, by means of interconnecting levers, can be operated by the usual margin release key (not shown) forming part of the key-board, so that when this key is depressed, the levers 16, 17 are caused to move downwardly and entirely out of the path of the rod 15. Thus, the typist can, by depressing this key, permit the rod 15 to proceed past the position of the margin stop levers and therefore permit typing beyond the predetermined margin in the usual manner.

It is the purpose of the present invention to provide as equally effective a margin stop for the bottom of the page, as has heretofore been provided for the side edges of the page, and preferably, to employ as far as possible, some of the parts of the usual margin indicating and stop devices that have heretofore been provided on standard machines, so as not to unduly complicate the typewriter by considerable additional mechanism. Referring more particularly to Figures 3, 4 and 5, reference character 18 designates the usual arcuate paper guide, the ends of which are secured to bridge elements 19 having oppositely disposed slots 20 for securing to the platen carriage. At about midway of this element, there is a slot 21 extending over a limited portion of the guide, and a rod or pintle 22 spans the sides of the slot 21

at the uppermost edge thereof. A strip of metal 23, slightly arcuate in form, is hinged in any suitable manner to the pintle 22 as indicated in Figure 5, this finger being provided with a pair of bearing surfaces 24, between which there is a torsional spring 25 surrounding the pintle rod 22. The spring is provided with legs 26, one of which is secured to the outer surface of the guide member 18, and the other secured to the outer surface of the finger 23. The arrangement is such that the spring 25 exercises a continuous urge on the finger to force it outwardly (as seen in Figure 4), but as explained hereinafter, this finger or lever is kept in restraint by the paper as it is being fed about the platen. The paper is illustrated at 27, and is fed around the platen 6 in clockwise direction, as indicated by the arrows, and as long as there is paper passing the lowermost edge 28 of the finger or lever 23, the latter is held against the platen 6. But as the paper proceeds together with the platen in a clockwise direction, and finally the edge 29 of the paper moves past the lower edge 28 of the lever, the latter is permitted to swing outwardly due to the removal of restraint of the paper and the urge of the spring 25.

On the opposite side of the paper from the lever 23, there is a second lever or finger pivoted at 31 to any suitable support 32 on the platen carriage. This lever takes the general form of a bell-crank having legs of unequal lengths, and the shorter leg 33 extending downwardly from the pivot point 31 to a position slightly below the end 28 of the lever 23. The longer leg 34 of the lever extends away from the platen, and preferably takes a curvilinear shape terminating at a position when not operated, which would carry it inside of the path containing the margin bell lever 16 and the margin stop lever 17. The hinge or pivot 31 preferably takes the form of a rod similar to the element 22 (Figure 5) which is spaced from, but secured to the inside surface of the well member 35 which surrounds the lower portion of the platen. As usual, this well member is formed integrally with a back-rest 36 as shown in Figure 2. The member 35 is provided with an opening 37 about mid-way of the length of the machine, this opening being sufficiently large to expose the short leg 33 of the bell-crank lever. A torsional spring, similar to element 25 (shown in Figure 5), is provided around the rod 31 on which the bell-crank lever is pivoted, this spring serving to cause the short leg 33 to move upwardly, i. e., in a clockwise direction (as seen in Figure 4), through the opening 37. This spring therefore urges the short leg 33 to move inwardly against the paper. However, the torsional spring 25 which tends to press the lever 23 outwardly, is capable of overpowering the torsional spring which surrounds the rod 31 and therefore is adapted to move the leg 33 counter-clockwise about its pivot when the restraining effect of the paper 27 is removed from the lever 23.

Operation

As explained hereinbefore, the margin bell-lever 16, and the margin yieldable stop lever 17 (Figure 4), are the usual accessories found on standard typewriters. The long leg 34 of the bell-crank lever is caused to pass on the inside of these two levers 16, 17, as the platen is moved during the typing operation, and when the predetermined lower margin has not been reached at the typing position. It will be understood that the levers 23, 33 are so positioned with respect to the platen, that when the bottom margin line

has been reached at the typing position, the edge 29 of the paper will have just passed the lower edge 28 of the lever 23, moving downwardly as indicated by the arrows. When this condition has arrived, the restraint on lever 23 exerted by the paper, is automatically removed so that the lever is permitted to move outwardly and to strike the short leg 33 of the bell-crank lever. This action causes the long arm 34 of the bell-crank to move from a position which would normally permit it to pass the levers 16, 17 as the platen is indexed across the machine into a path as will strike these two levers successively. Thus, the typist is forewarned by the bell ringing lever 16, that the permissible bottom margin line has been reached, and as the platen moves still further across the machine by operating the type, the platen is eventually brought to a full stop. However, in order to finish up the line, since it will be understood that the lever 17 takes effect when the platen has moved approximately half-way across the line to be typed, the typist can operate the margin release key to cause the lever 17 to be depressed in the usual manner, which would then permit the platen to proceed. The same thing happens on the next line, which may be one line lower than the permissible bottom margin, in that the typist in order to finish up the line, must again depress the margin release key so that at each line from the permissible margin on, she becomes conscious of the fact that the bottom margin has not only been reached, but also passed.

On the return trip of the platen at the end of each line, and still assuming that the lever 34 is in its outward position, and therefore normally contacts with the levers 16, 17, the lever 34 will normally ride over the margin levels 16, 17 and will meet no obstruction while the platen is being returned to typing position. It will be understood that the upper surfaces of the levers 16, 17 are so shaped as to force the lever 34 upwardly against its spring when the last-mentioned lever moves over the margin levers 16, 17.

While I have shown and described the position of the levers 23, 33 and 34 as being located approximately mid-way of the length of the platen carriage, it will be understood that if desired, these levers may be placed at any position along the length of the carriage and at either end thereof. However, I have found that under practical conditions, the mid-position for these levers is preferred, since the function of the improved mechanism is to apprise the typist that the bottom margin line has been reached, and this can be done quite as well at the middle of the line, as at either end.

From the foregoing, it is evident that I have disclosed a standard typewriter machine provided with an easily installed mechanism for giving the same indication, bell-ringing and stop functions in the case of the permissible bottom margin line, as heretofore has been provided in the case of the permissible side margin. The accessories for producing this added function can be readily applied to existing machines, since the levers 23, 33 and 34 are of an inexpensive and simple type, the only complicated mechanism being that already provided in the standard machines, namely, the margin bell lever 16 and the yieldable stop lever 17.

It will be understood that various modifications and arrangements in structure could be

made without departing from the spirit of my invention and, accordingly, I desire to comprehend such modifications and substitutions of equivalents as may be considered to come within the scope of the appended claims.

Having thus fully described my invention, what I claim as new and desire to secure by Letters Patent, is:

1. In a typewriter having a platen carriage, a side margin bell lever and a yieldable side margin stop lever controlling the locking of the keys of the typewriter, an arcuate paper guide secured to the platen carriage, mechanism comprising a lever swingably mounted on said guide and urged to move outwardly except when restrained by the paper wrapped around the platen, a bell crank lever having one leg pivoted so as to swing inwardly against the paper in the region of the first mentioned lever, a sheet of paper being typed when interposed between the first mentioned lever and the said leg of the bell crank serving to hold the first lever against the platen, the other leg of the bell crank being positioned so as to swing into the path of the side margin bell lever and the yieldable side margin stop lever when the lower edge of the paper moves past the first mentioned lever and by successive engagement with said levers to give a bell warning that the lowest permissible line of typing has been reached, and later to lock the keys as the platen carriage continues to move transversely of the typewriter.

2. In a typewriter having a platen carriage, a side margin bell lever and a yieldable side margin stop lever controlling the locking of the keys of the typewriter, an arcuate paper guide secured to the platen carriage, mechanism comprising a lever swingably mounted on said guide and urged to move outwardly except when restrained by the paper wrapped around the platen, a bell crank lever having one leg pivoted so as to swing inwardly against the paper in the region of the first mentioned lever, a sheet of paper being typed when interposed between the first mentioned lever and the said leg of the bell crank serving to hold the first lever against the platen, the other leg of the bell crank being positioned so as to swing into the path of the side margin bell lever and the yieldable side margin stop lever when the lower edge of the paper moves past the first mentioned lever and by successive engagement with said levers to give a bell warning that the lowest permissible line of typing has been reached, and later to lock the keys as the platen carriage continues to move transversely of the typewriter.

3. In a typewriter having a platen carriage, a side margin bell lever and a yieldable side margin stop lever controlling the locking of the keys of the typewriter, an arcuate paper guide secured to the platen carriage, mechanism comprising a lever swingably mounted on said guide and urged to move outwardly except when restrained by the paper wrapped around the platen, a bell crank lever having one leg pivoted so as to swing inwardly against the paper in the region of the first mentioned lever, a sheet of paper being typed when interposed between the first mentioned lever and the said leg of the bell crank serving to hold the first lever against the platen, the other leg of the bell crank being positioned so as to swing into the path of the side margin bell lever and the yieldable side margin stop lever when the lower edge of the paper moves past the first mentioned lever and by successive engagement with said levers to give a bell warning that the lowest permissible line of typing has been reached, and later to lock the keys as the platen carriage continues to move transversely of the typewriter, and means for moving the side margin bell lever and the yieldable side margin stop lever out of the path of said other leg of the bell crank in order to prevent the operation of the bell and the locking of the keys whereby additional lines can be typed on the paper.

PHILIP J. LINSKEY.
